CLAIM

The ornamental design for a motor mounting for a fan assembly, as shown and described.

DESCRIPTION

FIG. 1 is a front elevational view of a motor mounting for a fan assembly, showing my new design;

FIG. 2 is a front elevational view thereof, on a reduced scale;

FIG. 3 is a rear elevational view thereof, on a reduced scale;

FIG. 4 is a side elevational view thereof, the opposite side being a mirror image thereof; and,

FIG. 5 is a side elevational view thereof taken along lines 5—5 in FIG. 4.

The broken-line showing of a fan housing in FIGS. 2—5 is for illustrative purposes only and forms no part of the claimed design.
